WORK GUIDING MEANS FOR SEWING MACHINES

Application filed February 28, 1929. Serial No. 343,533.

This invention relates to improvements in work-guiding attachments for sewing machines and has for its primary object to provide means for facilitating the positioning of the work preparatory to commencing a stitching operation.

In its preferred embodiment, the present invention comprises a tape-guide positioned with respect to a hemmer to direct an elastic tape within a hem-fold, formed in a body material by said hemmer and before the hem-fold is stitched. The tape-guide is slidingly supported for retraction from the hemmer and is provided lengthwise thereof with a threading slit permitting ready introduction of a tape into its guide. Preferably, the tape-guide is made in sections, of which one is disposed substantially parallel with a line of seam formation and within the folding scroll of the hemmer, the tape being delivered to said section by another section disposed substantially transverse thereto. Suitable means is provided for imposing a tension upon an elastic tape directed by said tape-guide.

Considerable difficulty has heretofore been experienced in positioning under a sewing machine presser-foot the beginning end of work comprising a body material embracing a tensioned elastic tape, whereby the stitching operation may be started and continued with the tape under the requisite tension. In order to overcome this difficulty, the present invention comprehends the employment of a sewing machine presser-foot having relatively yielding work-engaging members of which one is spring-pressed to engage the tensioned tape and nip it against the machine throat-plate or feed-dog when the other presser-foot members are raised in the usual manner for introduction thereunder of the body material. The tape being under its regular tension as it is pulled through its guide preparatory to nipping the end of the tape by the presser-foot member and the delivering section of the tape-guide being disposed within the folding scroll of the hemmer, it is apparent that the body material may be readily manipulated by the operator preparatory to commencing the stitching operation and that

the stitching may be begun and continued with a controlled tension of the tape.

In the accompanying drawings, Fig. 1 is a front end elevation of a sewing machine containing the present improvement, showing a short length of tape and also a section of the body material to be stitched. Fig. 2 is a sectional view substantially on the line 2-2 of Fig. 3, with the presser-foot raised and the body material introduced thereunder shown in section. Fig. 3 is a front side elevation of a portion of the sewing machine having the attached work-guides. Fig. 4 is a top-plan of a portion of the sewing machine cloth-plate and attached guide, showing also a top-plan of the presser-foot. Fig. 5 represents in perspective the component parts of the presser-foot in detached relationship. Fig. 6 is a perspective view of the tape-guide.

Referring to the drawings, a sewing machine to which the present improved work-guide has been attached comprises a cloth-plate 1, suitably supported by a bed-plate 2 and having a throat-plate 3. Overhanging the cloth-plate is a bracket-arm terminating in a head 4 in which is journaled for vertically reciprocatory movements a needle-bar 5 carrying, in the present instance, two spaced needles 6 and 7 disposed in a line inclined to the line of seam formation. Cooperating with the needles in the formation of double-chain stitches are thread-carrying loopers 8 and 9 disposed below the throat-plate 3 and actuated to move crosswise of the line of seam formation in any suitable manner.

Projected through the throat-plate 3 is a work-advancing feed-dog 10 having actuating mechanism (not shown) which may be of any usual lower four-motion type of feeding mechanism. Opposed to the feed-dog 10 is a presser-foot having its shank 11 suitably secured to the lower end of a presser-bar 12 vertically movable in the head 4 in the usual manner.

The presser-foot shank 11 rises from a supporting block 13 provided in its under side with a square sided recess 14. Entering the block-recess 14 is the reduced and squared heel 15 of a presser-foot member 16 pivot-

ally secured upon the block 13 by means of a hinge-pin 17 disposed in aligned apertures 18 provided in said block 13 at opposite sides of the block-recess 14. Bearing yieldingly 5 against the base of the block-recess 14 is a coil spring 19 seated in a suitable socket 20, provided in the presser-member heel 15 rearwardly of the pivotal axis of said member. The presser-foot member 16 has at its front 10 end a turned-up toe 21 and is provided in the rearward end of its wider portion with needle-apertures, as 22 and 23, so located that the reduced heel 15 of said presser-foot member is disposed entirely between the seams formed 15 by the spaced needles 6 and 7.

Disposed at opposite sides of the heel 15 of the presser-foot member 16 and underlying the block 13, are presser-foot sections 24 and 25, each provided with spaced up- 20 standing guide-pins, as 26 and 27 slidingly disposed in substantially vertical apertures, as 28, provided in the block 13 at opposite sides of the presser-foot shank 11. Adjustably secured upon the protruding end of 25 each of the guide-pins 27 is a collar 29 which by engaging the upper surface of the block 13 limits the downward movement of the presser-foot sections 24, 25 relatively to said block. Engaging the upper sides of the 30 presser-foot sections 24, 25 are coil springs, as 30, seated in suitable sockets, as 31, provided in the presser-foot block 13. It is apparent from the foregoing description that the presser-foot sections 24 and 25 may yield 35 bodily to different thicknesses of work independently of each other and with respect to the presser-foot member 16, in the properly set height of the presser-bar 12. It is likewise apparent that the presser-foot member 40 16 may perform tilting movements to accommodate uneven portions of work and also that the heel 15 of said member will be yieldingly pressed downwardly by the spring 19 when the presser-bar 12 is raised. For insertion 45 and removal of work, the presser-bar 12 may be raised in any usual manner, as by means of a hand lifter-lever 32 or by means of suitable treadle-connections. (Not shown.)

Extending upwardly from the rearward 50 side of the bed-plate 2 is a bracket 33 in which is journaled the shaft 34 of a pull-feed wheel 35 which may be operated by any suitable actuating connections. Yieldingly opposed to said feed-wheel 35 is a presser-wheel 55 36 at the lower end of an auxiliary presser-bar 37 depressed by a spring 38. The auxiliary bar 37 is vertically movable in bearings provided in a bracket 39 extending rearwardly from the head 4 and may be raised 60 independently of the main presser-bar 12 by means of a lifter-lever 40 fulcrumed upon the bracket 39.

The work-guiding attachment which is disposed in advance of the stitch-forming mechanism comprises means for directing a ten-

sioned elastic-tape into a garment hem-fold as the latter is formed. To this end, an angular supporting-plate 41 is fastened by screws, as 42, upon the cloth-plate 1 to overhang a portion of the front side of the latter. Secured by a screw 43, upon the supporting-plate 41 for adjustment crosswise of the line of seam formation is the shank 44 of a hemmer having spaced outer and inner scroll portions 45 and 46 providing between them a curved passageway shaped to fold the margin of a body material downwardly and turn in the edge thereof. The inner scroll portion 46 is extended laterally to provide a work-supporting apron 47, the free end of which is preferably sustained by a bracket 48 secured upon the supporting plate 41 by a thumb-screw 49 for adjustment crosswise of the line of seam formation.

Underlying the apron 47 are tape-guide 85 sections 50 and 51 provided upon a tape-guide carrier 52 so as to successively direct a tape in substantially transverse directions. Projecting from the carrier 52 is a slide-bar 53 disposed in a suitable guideway provided by 90 spaced guide-blocks 54 upon the supporting plate 41, said slide-bar being shiftable in its guideway in a line substantially parallel with the line of seam formation. The inward movement of the slide-bar is limited by a 95 stop-screw 55, upon the under side of the slide-bar 53 and engageable with the depending portion of the supporting-plate 41. The slide-bar 53 is preferably latched in the operative position of the tape-guide and to this 100 end a spring 56 is secured by screws 57 upon the guide-blocks 54 to overlie the slide-bar 53. The free end of the spring is provided with a knob 58 adapted to enter a suitable recess formed in the upper side of the slide-bar 53. 105

The tape-guide section 50 comprises a flattened tube disposed substantially crosswise of the line of seam formation, the tape-receiving end 60 being inclined to the direction of passage of a tape through said section. At its 110 rear side, the tube section 50 has a threading slit 61 extending throughout the length of the tube to provide for introduction of the tape laterally into said section. Depending from the carrier 52, in front of the guide-section 50 is a finger-piece 62 for conveniently shifting said carrier in its guideway.

The delivery end 63 of the tape-guide section 50 is disposed adjacent and below the tape-receiving end 64 of the tape-guide section 51, which is positioned within the scroll portion of the hemmer in the direction of the line of seam formation. The tape-guide section 51 is also provided with a threading slit 65 extending throughout the length of the side thereof opposite to the side from which the tape is delivered to said section 51. Disposed in a plane between the delivery end 63 of one guide-section and the receiving end 64 of the other is an inclined guide-edge 66 115 120 125 130

over which the tape is led, thereby inverting said tape as it is delivered to the guide-section 51. The guide-edge 66 terminates adjacent the receiving end 64 in an upstanding lip 66'.

3. Suitably secured upon the depending portion of the supporting plate 41 is a flat tension-plate 67 and an oppositely directed bent, guide-pin 68 beneath which the tape is led. 10 Extending from said plate 41, through a suitable aperture (not shown) in the plate 67 is a tension-post 69 carrying an adjusting nut 70, between which and the tension-plate 67 is disposed a coil spring 71, whereby the tension exerted by the plate 67 upon the tape 15 may be regulated.

To prepare for the stitching operation, an elastic tape T is directed under the guide-pin 68 and tension-plate 67 and upwardly into 20 the tape-guide section 50, the tape-guide having been first retracted from its operative position by pulling upon the finger piece 62 to permit threading of the tape laterally into 25 said section 50. The tape T is then led around the guide-edge 66 and laterally into 30 the tape-guide section 51, with the end of the tape slightly protruding beyond the delivery end of the section 51. The tape-guide may now be returned to its operative position and 35 the tape drawn through the guide sections and inserted under the yieldingly depressed heel 15 of the presser-foot member 16 in the raised position of the presser-bar, said heel nipping the end of the tape against the throat-plate or feed-dog.

The depression of the heel 15 of the presser-foot by the spring 19 raises the toe 21 above the tensioned tape, whereby to provide clearance for the body material M which may now 40 be readily inserted into the hemmer in the usual manner and under the presser-foot, with the hem-fold embracing the tape. When the presser-foot is lowered upon the work, the sections 24 and 25 of the presser-foot engage 45 the work adjacent the longitudinal edges of the tape. In the present instance, the needles are spaced to penetrate the work adjacent the tape. The pull-feed mechanism referred to carries away the stitched work 50 and thereby prevents bunching of the work back of the presser-foot under the action of the tensioned tape.

Having thus set forth the nature of the invention, what I claim herein is:—

55 1. The combination with the stitch-forming mechanism of a sewing machine, of an edge-folder, a tape-guide extending within said edge-folder to direct a tape within a marginal fold formed in a body material by said edge-folder, and a sliding support for said tape-guide extending in a direction substantially parallel with the line of seam formation permitting retraction of the tape-guide from the edge-folder.

60 2. The combination with the stitch-form-

ing mechanism of a sewing machine, of an edge-folder, a tape-guide extending within said edge-folder to direct a tape within the marginal fold formed in a body material by said edge-folder, and a slidable tape-guide 70 support extending in a direction substantially parallel with the line of seam formation permitting ready retraction of the tape-guide from said edge-folder, said tape-guide having one side open throughout the length thereof 75 to permit threading of the tape laterally into said tape-guide.

3. In a sewing machine having stitch-forming and work-feeding mechanisms, substantially horizontally disposed tape-guide sections 80 successively acting to direct a tape in substantially transverse directions in advance of said stitch-forming mechanism, each of said sections being open at one side to permit of threading the tape laterally thereinto and one of said sections extending in substantially the direction of feed of the tape past said stitch-forming mechanism, an edge-folder for folding the margin of a body material about the tape, a carrier for said tape-guide sections, and supporting means for said carrier providing for withdrawing the tape-guide sections from operative position in the general direction of one of said sections.

4. In a sewing machine having stitch-forming and work-feeding mechanisms, a plurality of substantially horizontally disposed tape-guide sections successively acting to direct a tape in substantially transverse directions of which one corresponds with the direction of feed, an edge-folder having a scroll portion embracing one of said sections, a work-supporting apron overlying the other tape-guide section, and tape-tensioning means.

5. In a sewing machine, in combination with stitch-forming mechanism including a reciprocating needle, a work-support, a tape-guide disposed in advance of said needle, tape-tensioning means, means for folding a body material about a tape passed through said tape-guide, and a presser-foot movable toward and from said work-support having spaced relatively-yielding work-engaging sections, said presser-foot including a pivotally supported member disposed between said relatively yielding sections to engage the tape, and means for tilting the heel-portion of said presser-foot member toward the work-support in the position of the 110 presser-foot retracted from said work-support.

6. In a sewing machine having stitch-forming mechanism including a pair of needles spaced crosswise of the line of seam formation, a work-support, work-feeding mechanism, a tape-guide disposed in advance of said stitch-forming mechanism to direct the tape between the needles, means rearward of the needles for holding the tape against move- 125

ment in a direction opposite to the direction of seam formation, a presser-foot bodily movable toward and from said work-support including a pivotally supported member having its work-engaging heel disposed entirely between the seam lines rearwardly of said needles, and yielding means for tilting the toe portion of said presser-foot member in front of the needles about the pivotal axis of said member and in a direction away from the work-support in the raised position of the presser-foot.

In testimony whereof, I have signed my name to this specification.

15 RUDOLPH J. SAILER.
